Primary Examiner — Jae Liang*Assistant Examiner* — Tia Ruth-Renee Polidori(74) *Attorney, Agent, or Firm* — Anderson Gorecki LLP(57) **CLAIM**

The ornamental design for a double wall wine glass, as shown and described.

DESCRIPTION

FIG. 1 is a top perspective view of my new design for a double wall wine glass.

FIG. 2 is a front elevation view thereof—the rear, left-side, and right-side elevation views being identical.

FIG. 3 is a top plan view thereof.

FIG. 4 is a bottom plan view thereof; and,

FIG. 5 is a cross-sectional view thereof, taken along line 5-5 in FIG. 3.

The broken line arrows in FIG. 5 depict cross-sectional indicia and form no part of the claimed design.

1 Claim, 5 Drawing Sheets
